UNITED STATES PATENT OFFICE.

BENJAMIN M. CARR, OF HOUSTON, TEXAS.

CAR-WHEEL CHILL.

No. 872,608.

Specification of Letters Patent.

Patented Dec. 3, 1907.

Application filed April 6, 1907. Serial No. 366,741.

To all whom it may concern:

Be it known that I, BENJAMIN M. CARR, a citizen of the United States, residing at Houston, in the county of Harris and State 5 of Texas, have invented a new and useful Car-Wheel Chill, of which the following is a specification.

The present invention relates to contracting chills for car wheels and the like, and the 10 principal object of the present invention is to provide a novel, simple, durable and comparatively inexpensive chill that can be manufactured with a minimum amount of dressing or machine work, will retain its 15 shape and hold the parts in properly associated relation, provides means for effectively venting the gases, and can be handled and used in connection with the ordinary foundry mechanism.

20 The preferred embodiment of the invention is illustrated in the accompanying drawings: wherein:—

Figure 1 is a plan view of the chill. Fig. 2 is a horizontal sectional view through a 25 portion thereof. Fig. 3 is a detail sectional view on the line 3—3 of Fig. 2. Fig. 4 is a cross sectional view on the line 4—4 of Fig. 2. Fig. 5 is a cross sectional view on the line 5—5 of Fig. 2. Fig. 6 is a detail perspective view of a segment of one of the pairs. Fig. 7 is a similar view of the other segment 30 of a pair.

Similar reference numerals designate corresponding parts in all the figures of the 35 drawings.

In the embodiment illustrated, the chill is composed of an inner portion, and an outer portion or body. The inner portion consists of a circular series of radially disposed 40 segments, which are arranged in pairs. As each pair is a duplicate of the other, a description of one is believed to be sufficient for all. The pair is composed of what may be termed "right" and "left" segments 8 and 9, which have flat abutting faces 10. The pair is provided at its rear end with an upright extension, in the form of a dovetail that comprises sections 11 carried respectively by the segments and of less thickness 45 than the pair, as illustrated in Fig. 2. This dovetail is thus formed partially on each segment, and the opposing or abutting faces of the sections 11 are provided with alined upright recesses 12 producing an inclosed 50 upright drag pin receiving socket in each pair of segments, as clearly shown in Figs. 1

and 2. The rear end of the dovetail 11 is furthermore provided with a transversely disposed dovetail 13 extending across the central portion of the dovetail 11 and carried partially by each section thereof, as will be evident Figs. 6 and 7.

The outer faces 14 of each pair of segments are provided with upwardly tapered recesses 15 that coöperate or aline with corresponding recesses in the outer faces of the adjacent pairs, thereby producing upright tapered vent conduits, as shown in Fig. 2. The segments having the abutting outer faces 14, are thus arranged in sets, having 70 dovetail sockets 16 formed therein between the dovetails 11 of the pairs. Certain of the said faces 14 are furthermore provided with upper and lower flanges or ribs 17, and when the segments are constructed, said faces are 75 also preferably provided with upright flanges 18. These flanges constitute bearings that are from one sixty-fourth to one thirty-second of an inch thick, and serve to space the adjacent opposing walls apart, thereby 80 forming channels 19, as shown in Fig. 3, which communicate with the conduits 15, for the purpose of permitting the escape of gases from the mold.

In constructing the chill, the segments 85 above described, as cast, are arranged in sets or pairs side by side, as illustrated in Figs. 1 and 2, and an outer body or ring 20 is then cast around the outer ends thereof, said body 90 inclosing the transverse dovetails 13, as illustrated in Figs. 4 and 5, and interlocking with the upright dovetails 11, inasmuch as the metal flows into the dovetail sockets 16, thereby producing dovetails 21 between the dovetails 11. This effectively holds the segments 95 in position as illustrated. The inner face of the chill, as thus produced, is then bored out and this boring besides truing the inner face, takes away the flanges 18, leaving the channels 19 opening through the inner 100 face of the chill. The wheel is then cast in the ordinary manner, and the said channels 19 while allowing the escape of the gases from the mold, leave but small marks or impressions on the face of the wheel, which can 105 be readily ground off. It will be observed that in the construction of the chill, no core work is required, and it is not necessary to saw the sections or segments. Moreover the chill is used with the regular coop and drag 110 ring, and inasmuch as but two styles of segments are required, the "right" and "left",

these segments can be very cheaply produced, and require no machine work, except in boring out the inner face of the chill. Experience has demonstrated that with this structure, the strain is evenly distributed so that the chill will retain its shape, and will always produce a wheel that is perfectly round.

While only two drag pins are ordinarily employed in operating the chill, the large number of drag pin-receiving sockets is important for two reasons. In the first place, the drag pins can be moved to different points to receive the drag ring, and secondly, the sockets constitute additional vents to permit the escape of gas from the mold.

It is well known to those skilled in the art that contracting chills are old devices and in every case heretofore so far as I am aware, the projecting sections are entirely spaced apart throughout their width, and are usually sawed, an operation that requires a very considerable length of time and amount of expense. Besides the sections are as a consequence spaced a considerable distance apart, at least three thirty-seconds of an inch, allowing the hot iron to flow into these spaces and attack the metal so that the chill is soon warped and destroyed. As distinguished from this, the chill sections constructed in accordance with the present invention have a space only one-thirty-second of an inch between them, which allows the gases free vent, preventing the iron attacking the adjacent faces and leaving but the slightest marks on the cast wheel. Furthermore the spacing does not extend the entire width of the sections, because of the flanges which by bearing against the adjacent sections, serve to prevent lateral displacement of the sections under the various strains necessarily set up during the casting operation, and thus by maintaining said sections in proper relative position, insure long life to the chill.

From the foregoing, it is thought that the construction, operation, and many advantages of the herein described invention will be apparent to those skilled in the art, without further description, and it will be understood that various changes in the size, shape, proportion, and minor details of construction, may be resorted to without departing from the spirit or sacrificing any of the advantages of the invention.

Having thus fully described my invention, what I claim as new, and desire to secure by Letters Patent, is:—

1. A chill of the character set forth having an inner portion comprising a series of segments located side by side, certain of the adjacent segments having recesses in their opposing sides and having said opposing sides abutted on opposite sides of the recesses forming open-ended inclosed vent channels.

2. A chill of the character set forth having

an inner portion comprising a series of segments located side by side, certain of the adjacent segments having recesses in their opposing sides and having said opposing sides abutted on opposite sides of the recesses forming inclosed vent conduits, and spaced flanges carried by the upper and lower portions of certain of the opposing faces and abutting against the other faces forming open ended vent channels between the segments that communicate with the said conduits.

3. A chill of the character set forth including sets of segments, the segments of each set having alined recesses in their opposing faces forming an inclosed vent conduit, one of the opposing faces having spaced longitudinal flanges that abut against the other face forming an open ended channel between them that communicates with the conduit, the outer faces of the segments of each set being flat and abutting against the outer flat faces of the adjacent sets.

4. A chill of the character set forth, including sets of segments having alined recesses in their opposing faces, the said faces on the opposite sides of the recesses being abutted, forming inclosed drag pin receiving sockets.

5. A chill of the character set forth, including a plurality of segments located side by side, each segment having recesses in its opposite sides that aline with the corresponding recesses in the opposing sides of the adjacent segments, forming vent conduits and drag pin receiving sockets.

6. A chill of the character set forth, including a plurality of segments located side by side each segment having recesses in its opposite sides, said recesses being located at different distances from the inner end of the segment and alining with corresponding recesses in the opposing sides of the adjacent segments forming vent conduits and drag pin receiving sockets.

7. A chill of the character set forth, including a plurality of segments located side by side, each segment having recesses in its opposite sides, said recesses being located at different distances from the inner end of the segment and alining with corresponding recesses in the opposing sides of the adjacent segments forming vent conduits and drag pin receiving sockets, certain of the opposing sides moreover having spaced flanges that abut against the coöperating sides of the adjacent segments, forming vent channels that communicate with the conduits.

8. A chill of the character set forth, including a plurality of sets of segments, each set having rearwardly projecting abutting extensions of less width than the segments, and a holding body interlocked with said extensions and securing the same together.

9. A chill of the character set forth, including a plurality of sets of segments, each set having a rearwardly projecting dovetail

formed of abutting sections carried partially by each segment, and a holding body interlocked with said dovetail and holding the same together, said dovetail sections having recesses in their abutting faces forming sockets in said dovetail.

10. A chill of the character set forth, including a plurality of sets of segments, each set having a rearwardly projecting dovetail formed of abutting sections carried partially by each segment, and a holding body interlocked with said dovetail and holding the same together.

11. A chill of the character set forth, comprising a plurality of sets of segments, each set having a rearwardly projecting dovetail formed partially on each segment of the set, a dovetail disposed transversely of and projecting from the rear end of the first mentioned dovetail, and a holding body cast about the various dovetails for securing the segments in associated relation.

12. A chill of the character set forth, comprising an inner portion composed of a circular series of segments arranged in pairs, each pair of segments having a rearwardly extend-

ing dovetail of less thickness than the pair and formed partially on each segment, another dovetail disposed transversely of and projecting from the rear end of the first mentioned dovetail, said first mentioned dovetail having an upright socket formed partially in each section thereof, the outer faces of each pair of segments being provided with upright recesses coöperating with the recesses in the outer faces of the adjacent pairs, forming vent conduits, flanges formed upon certain faces of the pairs and abutting against the outer faces of adjacent pairs, forming vent channels that communicate with said conduits, and a circular holding body cast around the outer ends of the segments and interlocking with the various dovetails thereof to secure said segments in associated relation.

In testimony, that I claim the foregoing as my own, I have hereto affixed my signature in the presence of two witnesses.
